His Attorney.

UNITED STATES PATENT OFFICE.

FREDERICK D. WALLING, OF EAST ALTON, ILLINOIS, ASSIGNOR TO WESTERN CARTRIDGE COMPANY, OF EAST ALTON, ILLINOIS, A CORPORATION OF DELAWARE.

TARGET TRAP.

Application filed December 30, 1922. Serial No. 609,918.

To all whom it may concern:

Be it known that I, FREDERICK D. WALLING, a citizen of the United States, and residing at East Alton, county of Madison, Illinois, have invented the new and useful Improvement in Target Traps, of which the following is a specification.

This invention relates to target traps, such as are used for throwing clay targets in shooting contests and the like.

As is well known the traps of this kind are ordinarily provided with a throw arm, spring operated to throw the target into the air. On some types of traps the throw arm is provided with a carrier flexibly connected thereto which carries the target. Upon release of the throw arm, the movement thereof operates to deflect the carrier against the tension of the spring, which spring in turn operates to give the carrier a sort of whipping movement at the end of the swing of the throw arm so as to project the target into the air with greater force. The carrier is usually pivoted on the throw arm and the restraining spring operates to hold the carrier in alinement, except during the throwing movement when the above-mentioned deflection takes place. When the throw arm is swung backward to set the trap, it engages an abutment or stop in the rearward position at the point in its movement where the catch is engaged for holding it in the set position. As the setting movement takes place rapidly, the arm usually comes against the stop with considerable force and the carrier on account of its flexible mounting on the throw arm is set into more or less violent oscillation on the throw arm. An appreciable time is required for this oscillation to subside and the trap cannot be reloaded until such oscillation does subside without some danger of injury to the operator.

One of the objects of this invention, therefore, is to provide a trap in which the oscillation of the carrier on the throw arm, due to the resetting movement, may be damped so that the throw arm may be quickly brought to rest for reloading the trap.

Another object of this invention is to provide such a trap which shall be simple and

cheap to manufacture, and durable in service.

Further objects will appear from the detail description taken in connection with the accompanying drawing, in which:

Figure 1 is a side elevation showing a target trap embodying this invention; and

Figure 2 is an enlarged detail plan view of the end of the throw arm and the carrier thereon.

Referring to the accompanying drawing, 1 designates a frame having at its rearward end a standard 2 and at its forward end a post 3. The frame 1 is pivoted at 4 to a support 5 upon which it is adjustably mounted so that it may be set at different angles, the same being fixed by means of a clamping bolt 6. The post 3 supports a shaft 7 which carries at its upper end a throw arm 8 by means of which the targets may be thrown into the air. The shaft 7 has fixed thereto an arm 11 to which is attached one end of a spring 12, the other end of which is attached to an adjustable bolt 13 on the standard 2. The spring 12 acting through the arm 11 is adapted to tension the throw arm 8.

The shaft 7 carries a sprocket 14 which is engaged by a chain 15 connected to an actuator 16 pivoted at 17 on the standard 2. The actuator 16 is connected with an operating rod or tube 18. The element 18 should be a stiff rod or tube capable of transmitting a thrust as well as a pull. Tension on the rod 18 operates to move the actuator 16 to the left, Figure 1, thereby through the agency of the chain 15 rotating the sprocket 14 and the shaft 7 against the tension of the spring 12 so as to swing the arm 8 rearwardly to set the trap. The arm 8 is provided with an extension 19 having a notch 20 adapted to engage a sear 21 to hold the arm against the tension of the spring 12 while the trap is set.

The sear 21 is slidably mounted upon the standard 2 for movement to the right or left, Figure 1, and is guided by a pin 22 working in a slot in the sear. The sear 21 is held in retracted position by a spring 24.

Pivoted at 25 on the actuator 16 is a trigger 26 provided at one end with an abutment 27 adapted to engage the rearward end

of the sear 21. The trigger 26 is further provided with an abutment 28 adapted to engage a stationary abutment 29 on the standard 2 when the actuator 16 is moved to the right.

The arm 8 carries near its free end a pivot pin 31 upon which is pivotally mounted a carrier 30 in which the target may be placed. A spring 32 is anchored at one end on a pin 33 on the arm 8 and engages at its other end a pin 34 on the rear end of the carrier 30. The tension of the spring 32 operates to draw back the rear end of the carrier so as to position the carrier in a forwardly extending position. The pivot pin 31 carries thereon a coil spring 35, one end of which is anchored to the pin and the other end of which is formed into a hook 36 adapted to engage the pin 34. The spring 35 is held in a stationary position by being anchored to the pin 31, which is stationary with respect to the arm 8. As will be seen from Figure 2, the carrier 30 can be moved to dotted line position against the tension of the spring 32 and the pin 34 will move away from the hook 36 of the spring 35 so that movement of the carrier in this direction is in no way affected by the spring 35. Return movement of the carrier, however, under the influence of the spring 32 will bring the pin 34 against the hook 36, said pin forming an abutment to limit the movement of the carrier in that direction.

In the use of this device the operator pulls the rod 18 to the left, Figure 1, usually by means of a suitable lever arrangement at the firing point. This moves the actuator 16 to the left, pulling the chain 15 so as to rotate the sprocket 14 and the shaft 7, thereby swinging the arm 8 to the rear until the notch 20 engages the sear 21. The sear will then hold the arm in its rearward position when the trap is set. An attendant then places a target in the carrier 30. When the contestant is ready to fire the operator pushes forward or to the right, Figure 1, on the rod 18, thereby moving the actuator 16 to the right. Upon completion of this movement by the actuator, the abutment 28 of the trigger 26 will strike the stationary abutment 29, being arrested thereby. As the actuator 16 continues its forward movement, the trigger 26 is forced to pivot about the pin 25, thereby forcing the abutment 27 sharply into engagement with the rearward end of the sear 21. The impact moves the sear 21 to the right, Figure 1, and releases the arm 8 whereupon said arm is thrown forward by the action of the spring 12. This movement is sudden and as the arm 8 starts to swing, the carrier 30 by its inertia, moves to the dotted position, Figure 2, until near the completion of the swing of the arm 8 when

the spring 32 returns the carrier 30 to its forwardly extending position with a sharp whip-like movement which discharges the target into the air.

The trap must now be reset as previously described by moving the rod 18 to the left, Figure 1. Upon resetting the trap, the arm 8 strikes against the frame 2 which arrests its movement with a jar. In the absence of the spring 35, this would have a tendency to set the carrier 30 into violent oscillation about the pivot 31 and the attendant must wait until such oscillation subsides before reloading the trap. With the present invention the spring 35 engaging the pin 34 will quickly damp such oscillation so as to bring the carrier to rest in a very short time and the attendant can immediately reload the trap.

It will thus be seen that by providing the spring 35 to engage the pin 34 upon the resetting movement, the overtravel of the carrier is restrained and oscillation thereof is thereby quickly damped.

It is obvious that various changes may be made in details of construction without departing from the spirit of this invention; it is, therefore, to be understood that this invention is not to be limited to the specific details shown and described.

Having thus described the invention, what is claimed is:

1. A target trap comprising, a throw arm adapted for swinging movement to set position, means for arresting such movement in set position, a carrier pivotally mounted and yieldingly alined on said arm so as to provide for a throwing movement, and a yielding bumper adapted to prevent oscillation of said carrier upon the arrest of said setting movement.

2. A target trap comprising, a throw arm adapted for swinging movement to set position, means for arresting such movement in set position, a carrier pivotally mounted and yieldingly alined on said arm so as to provide for a throwing movement, an abutment on said carrier, and yielding means engaging said abutment adapted to restrain the rebound of said carrier upon arrest of said setting movement.

3. In a target trap, a throw arm, a carrier pivotally mounted on said arm and yieldingly alined thereon so as to provide for a throwing movement, and a return bumper for said carrier.

4. In a target trap, a throw arm, a carrier pivotally mounted on said arm and yieldingly alined thereon so as to provide for a throwing movement, and a yielding return bumper for said carrier.

In testimony whereof I affix my signature this 6th day of October, 1922.

FREDERICK D. WALLING.
